UNITED STATES PATENT OFFICE.

AMERICUS C. MILLS, JR., OF ROCHESTER, NEW YORK.

DESIGN FOR A HAT-HOLDER.

SPECIFICATION forming part of Design No. 34,699, dated June 25, 1901.

Application filed May 22, 1901. Serial No. 61,464. Term of patent 3½ years.

To all whom it may concern:

Be it known that I, AMERICUS C. MILLS, Jr., a citizen of the United States, residing at 17
Lawn street, Rochester, in the county of Monroe and State of New York, have invented
and produced a new and original Design for a Hat-Holder, of which the following is a
specification, reference being had to the accompanying drawing, forming a part thereof.

The drawing shows a perspective view of a
hat-holder embodying my design.

As shown, the leading feature of the design is the shape or configuration of the holder,
embodying four radiating members or arms
1, each having their inner and outer portions
in different horizontal planes, between which

are substantially vertical connecting portions. The arms radiate from a central double coil, (indicated by 2,) two of them extending outwardly directly from the top of the coil, and two others have the curved portions 3 extending from the lower portion of the coil upwardly into the plane of the top of the coil before extending outwardly, as shown.

I claim—

The design for a hat-holder substantially as herein shown and described.

AMERICUS C. MILLS, JR.
